UNITED STATES PATENT OFFICE

CARL LITTLEFIELD, OF BATTLE CREEK, MICHIGAN, ASSIGNOR TO BATTLE CREEK
BREAD WRAPPING MACHINE CO., OF BATTLE CREEK, MICHIGAN

WRAPPING MACHINE

Application filed August 1, 1928. Serial No. 296,867.

- The main objects of this invention are: First, to provide in a wrapping machine an improved means for performing the initial wrapping operation and supporting the package in its initial wrapping position. 5 Second, to provide an improved means for wrapping articles such as boxes having telescoping covers, that is, covers which project over the walls of the box. 10 Third, to provide a wrapping mechanism in which the wrapper is smoothly applied and snugly fitted to the angles of the box. 15 Objects pertaining to details and economies of my invention will definitely appear 15 from the detailed description to follow. The invention is defined in the claims. 20 A structure embodying the features of my invention is clearly illustrated in the accompanying drawings, in which: Fig. 1 is a side perspective view of my improved wrapping machine, parts being broken away for convenience in illustration. 25 Fig. 2 is an enlarged perspective view showing details of the folding mechanism, the parts being in initial or retracted position. 30 Fig. 3 is a fragmentary perspective view of certain parts shown in Fig. 2 in partially advanced position. Fig. 4 is a fragmentary perspective view 35 with a package in its initial wrapping position and the wrapper draped over the same. Fig. 5 is a fragmentary perspective view 40 with the front end bottom flap folders in partially actuated position. Fig. 6 is a fragmentary perspective view 45 showing the partially wrapped package at another state in its travel, the initial folding of the rear end flaps having been performed. 50 Fig. 7 is a fragmentary perspective view showing the package at another state of its travel, in position where the initial folding of the top and bottom end flaps is begun. Fig. 8 is a transverse section through the delivery conveyor on a line corresponding to line 8-8 of Fig. 7. 55 Fig. 9 is a perspective view of the wrapped package. 60 Referring to the drawings, the frame des- ignated generally by the numeral 1 is of suitable construction to support the operative parts. The packages to be wrapped are fed into the machine by the conveyor shown conventionally at 2. As the details of this conveyor form no part of the present invention they are not shown herein. 55 From this feed conveyor the packages are delivered to a vertically reciprocating plunger 3. The means for reciprocating this plunger in timed relation with the other parts are not illustrated as they form no part of this invention. 60 The wrappers 4 are fed into position above the plunger by means of a wrapper feed mechanism disposed at the front of the machine and designated generally by the numeral 5. The wrappers are fed on to a supporting table 6 having an opening therein through which the plunger reciprocates. 70 As the packages are carried upwardly by the plunger they engage the under side of the paper centrally thereof so that as the package is advanced the wrapper is draped over the sides by its wiping engagement with the front edge of the bottom front flap folder 7 and the front edge of the rear bottom flap folder 8. The rear bottom flap holder 8 is stationary while the front flap folder 7 is mounted for reciprocatory movement. 75 In coacting relation to the member 8 I provide a plurality of wrapper holding fingers 9 which are mounted on a shaft 10 to project upwardly when in one position in the plane at the front edge of the flap folder 8, 80 see Fig. 3, or to project forwardly therefrom as shown in Fig. 2, or to lie in the slots 11, 85 also shown in Fig. 2. These fingers are arranged in oppositely projecting pairs. 90 A cam-shaped locking member 12 provided with a pair of stop shoulders 13 is mounted on the end of the shaft to coact with a dog 14 pivoted at 15 and urged yieldingly to engaging position by the spring 16. This dog is automatically released by the cam 17 on the shaft 18 which is driven in timed relation to other parts of the machine. The dog 95 is released in timed relation to the upward travel of the plunger 3 so that as the wrapper on the box is carried into engagement 100

with the forwardly projecting fingers 9, the shaft may rotate so that the fingers wipe against or hold the wrapper and swing to the position shown in Fig. 3.

As the partially wrapped package is moved rearwardly over the flap folder 8 the fingers 9, which are then engaging the side of the package, swing downwardly into the slots 11. The fingers, however, maintain a frictional engagement with the wrapper, smoothly and snugly wrapping it about the side of the package.

When the package is moved upwardly to first flap folding position shown in Fig. 4, with a wrapper draped over the top and sides of the package, the wrapper rests against the under sides of the wrapper retaining bars 19. These bars are spaced so as to engage the wrapper adjacent the upper edges of the package which is shown at 20.

The package illustrated is provided with a cover 21, the edges of which overhang the sides of the box.

With the parts in position shown in Fig. 4 the front bottom flap folder 7 and also the front end flap folders 22 are actuated to fold the front bottom flap against the under side of the package and to fold the front end flaps against the ends of the package.

The front end flap folders 22 are mounted to move with the bottom flap folder 7, the folder 7 and attached parts which are carried by a slide 107 are connected by the link 23 to a lever 24 oscillated by the pitman 25 driven from the crank disk 26 on the shaft 18. The front end flap folders 22 have shouldered faces 27, the shoulders being positioned to fit under the cover of the box being wrapped. These end flap folders 22 carry centrally disposed forwardly projecting fingers 28 which engage the front end flaps centrally, initially deflecting or bending the same, which results in a more even or uniform fold and prevents wrinkles, reducing the likelihood of fracturing the paper.

Movable with the bottom and end flap folders are wrapper retaining blades 29 which project forwardly to engage the portions of the wrapper projecting at the top of the box as shown in Fig. 4. These retaining blades engage the wrapper at the front top edge of the box as shown in Fig. 4 so that, as the front folds are formed slipping of the wrapper is prevented, and a smooth close fold over the edge of the package results.

Following these folding operations described the package is moved rearwardly by means of the pusher 30 which is movable independently of the front, bottom and end flap folders, and is shouldered at 31 to correspond with the shoulders on the faces of the front end flap folders 22. This pusher 30 is carried by a slide 32 connected to the rods 33, one of which is connected to the actuating lever 34 driven through the pitman

35. The actuating means for this pitman are not illustrated.

In synchronism with the engagement of the package with the pusher the dog 14 is released so that as the package is carried over the rear bottom flap folder 8 the fingers 9 wipe or turn the rear bottom flap under the package and swing down into the slots 11 in the member 8. Continued movement of the package brings the rear end flaps first into engagement with the rear end flap creasing fingers 36 which form the initial bend or deflection in the rear end flap as is clearly indicated in Fig. 6.

It will be observed that in this position the wrapper holding blades 29 have advanced so that they engage the wrapper at the rear top edge of the box, preventing upward buckling during this initial folding. It should also be noted that the wrapper retaining bars 19 are continued or extend to the rear of the folding mechanisms.

Continued rearward movement of the package brings it into engagement with the rear end flap folders 37 which are operatively fixed relative to the folding table 38 so that as the package is carried along thereon, the rear end flap fold is completed. These folders 37 have shouldered faces 39 as clearly shown in Fig. 3.

At the outer sides of the rear end flap folders 37 I mount top flap creasing members 40 which are curved downwardly and forwardly so that the projecting top flaps pass over the same, the ends of the holding blades 29 being in this position in coacting relation to the creasing members so that projecting top flaps are carried between these members as shown in Fig. 7. These creasing members insure a sharp smooth fold for the top end flap. To secure the same result for the bottom end flap I provide creasing fingers 41 which, as the partially wrapped package is carried rearwardly, engage the bottom end flaps, that is, the bottom end flaps pass under the same, thereby forming sharp creases in the previously folded flaps.

The top and bottom end flap folders 42 and 43 are positioned in opposed relation and conformed so that the bottom end flap is first folded upwardly and the top flap is then folded downwardly upon the folded bottom end flaps. The folding edges of the bottom end flap folders are inclined forwardly and downwardly, while the folding edges of the top end flap folders are inclined downwardly and rearwardly.

I preferably employ a sealing mechanism in this relation which, when the packages are wrapped with paraffined paper, melt the paraffin sufficiently to seal the overlying flaps. The end flap sealers are conventionally shown at 44 and are disposed at the rear of the top end flap folders 42. The bottom heating element is indicated by dotted lines at

45, Fig. 7. The end flap sealers 44 also have shouldered faces as indicated to correspond with the shouldered faces of the end flap folders.

5 From the sealing position the packages are passed to a delivery conveyor consisting of a slideway 46 and a pair of opposed belts 47 having shouldered faces 48 which not only have the advantage of firmly grasping the 10 sides of the package but also retain the end flaps of the wrapper until the sealing paraffin is cooled or set.

15 I have illustrated and described my improvements in a wrapping machine especially designed for the wrapping of boxes, although various features are desirable and readily adapted for embodiment and use in machines for wrapping other articles having smooth exteriors. I have not illustrated and 20 described various operating mechanisms and connections as these mechanisms may be considerably varied in accordance with the general design of the machine. It will be understood, however, that the actuation of the 25 plunger 3 and feeding of the wrappers, the actuation of the front flap folders and the pusher, and the releasing of the dog 14 must be properly synchronized.

Having thus described my invention what 30 I claim as new and desire to secure by Letters Patent is:

1. In a wrapping machine, the combination of a way, a feed plunger, a wrapper feed means, a pair of spaced wrapper retaining 35 bars disposed longitudinally above said way and extending above said feed plunger to engage the wrappers when in initial folding position and during the several folding operations, a rear bottom flap folder disposed at the front end of said way, a reciprocatingly mounted front bottom flap folder, front end flap folders operatively associated with said front bottom flap folder to reciprocate 40 therewith, said front end flap folders being provided with projecting centrally disposed flap bending fingers, a reciprocating pusher movable independently of said front end flap folders and adapted to reciprocate above the front bottom flap folder and between the front end flap folders, rear end flap folders 45 mounted at the sides of said way and provided with forwardly projecting centrally disposed flap bending fingers, a forwardly and downwardly curved top end flap creasing member disposed at the outer sides of said rear end flap folders, coacting creasing blades reciprocating with said front end flap folders and constituting supports for the front flaps during the folding of the front and rear 50 end flaps, bottom end flap creasing members disposed to act on the bottom end flap after the folding of the front and rear end flaps, top and bottom end flap folders disposed at the sides of the way, sealing members disposed at the rear of said flap folders, the

faces of said pusher, end flap folders and sealing members being shouldered to receive the projecting cover of a package, and a delivery conveyor comprising belts adapted to engage the sealed ends of the package and having stepped faces corresponding to the shouldered faces of the said folding and sealing members.

2. In a wrapping machine, the combination of a way, a feed plunger, a wrapper feed means, a pair of spaced wrapper retaining bars disposed longitudinally above said way and extending above said feed plunger to engage the wrappers when in initial folding position and during the several folding operations, a rear bottom flap folder disposed at the front end of said way, a reciprocatingly mounted front bottom flap folder, front end flap folders operatively associated with said front bottom flap folder to reciprocate therewith, said front end flap folders being provided with projecting centrally disposed flap bending fingers, a reciprocating pusher movable independently of said front end flap folders and adapted to reciprocate above the front bottom flap folder and between the front end flap folders, rear end flap folders mounted at the sides of said way and provided with forwardly projecting centrally disposed flap bending fingers, a forwardly and downwardly curved top end flap creasing member disposed at the outer sides of said rear end flap folders, coacting creasing blades reciprocating with said front end flap folders and constituting supports for the front flaps during the folding of the front and rear end flaps, bottom end flap creasing members disposed to act on the bottom end flap after the folding of the front and rear end flaps, top and bottom end flap folders disposed at the sides of the way, and sealing members disposed at the rear of said flap folders.

3. In a wrapping machine, the combination of a way, an article feed means, a wrapper feed means, a rear bottom flap folder disposed at the front end of said way, a reciprocatingly mounted front bottom flap folder, front end flap folders operatively associated with said front bottom flap folder to reciprocate therewith, said front end flap folders being provided with projecting centrally disposed flap bending fingers, a reciprocating pusher movable independently of said front end flap folders and adapted to reciprocate above the front bottom flap folder and between the front end flap folders, rear end flap folders mounted at the sides of said way and provided with forwardly projecting centrally disposed flap bending fingers, a forwardly and downwardly curved top end flap creasing member disposed at the outer sides of said rear end flap folders, coacting creasing blades reciprocating with said front end flap folders and constituting supports for the front flaps during the folding of the front and rear end flaps, bottom end flap creasing members disposed to act on the bottom end flap after the folding of the front and rear end flaps, top and bottom end flap folders disposed at the sides of the way, sealing members disposed at the rear of said flap folders.

4. In a wrapping machine, the combination of a way, an article feed means, a wrapper feed means, a rear bottom flap folder disposed at the front end of said way, a reciprocatingly mounted front bottom flap folder, front end flap folders operatively associated with said front bottom flap folder to reciprocate therewith, said front end flap folders being provided with projecting centrally disposed flap bending fingers, a reciprocating pusher movable independently of said front end flap folders and adapted to reciprocate above the front bottom flap folder and between the front end flap folders, rear end flap folders mounted at the sides of said way and provided with forwardly projecting centrally disposed flap bending fingers, a forwardly and downwardly curved top end flap creasing member disposed at the outer sides of said rear end flap folders, coacting creasing blades reciprocating with said front end flap folders and constituting supports for the front flaps during the folding of the front and rear end flaps, bottom end flap creasing members disposed to act on the bottom end flap after the folding of the front and rear end flaps, top and bottom end flap folders disposed at the sides of the way, sealing members disposed at the rear of said flap folders, the

- front flaps during the folding of the front and rear end flaps, bottom end flap creasing members disposed to act on the bottom end flap after the folding of the front and rear end flaps, top and bottom end flap folders disposed at the sides of the way, sealing members disposed at the rear of said flap folders, the faces of said pusher, end flap folders and sealing members being shouldered to receive the projecting cover of a package, and a delivery conveyor comprising belts adapted to engage the sealed ends of the package and having stepped faces corresponding to the shouldered faces of the said folding and sealing members.

6. In a wrapping machine, the combination of a way, an article feed means, a wrapper feed means, a rear bottom flap folder disposed at the front end of said way, a reciprocatingly mounted front bottom flap folder, front end flap folders operatively associated with said front bottom flap folder to reciprocate therewith, said front end flap folders being provided with projecting centrally disposed flap bending fingers, a reciprocating pusher movable independently of said front end flap folders and adapted to reciprocate above the front bottom flap folder and between the front end flap folders, rear end flap folders mounted at the sides of said way and provided with forwardly projecting centrally disposed flap bending fingers, a forwardly and downwardly curved top end flap creasing member disposed at the outer sides of said rear end flap folders, coacting creasing blades reciprocating with said front end flap folders and constituting supports for the front flaps during the folding of the front and rear end flaps, bottom end flap creasing members disposed to act on the bottom end flap after the folding of the front and rear end flaps, top and bottom end flap folders disposed at the sides of the way, and sealing members disposed at the rear of said flap folders.

7. In a wrapping machine, the combination of a way, a feed plunger, a wrapper feed means, a pair of spaced wrapper retaining bars disposed longitudinally above said way and extending above said feed plunger to engage the wrappers when in initial folding position and during the several folding operations, a rear bottom flap folder disposed at the front end of said way, a reciprocatingly mounted front bottom flap folder, front end flap folders operatively associated with said front bottom flap folder to reciprocate therewith, a reciprocating pusher movable independently of said front end flap folders and adapted to reciprocate horizontally above the front bottom flap folder and between the front end flap folders, rear end flap folders mounted at the sides of said way, top and bottom end flap folders disposed at the sides of the way, and sealing members disposed at the rear of said flap folders.

8. In a wrapping machine, the combination of a way, a feed plunger reciprocating transversely of said way, a wrapper feed means for delivering wrappers in the path of said plunger, a pair of spaced wrapper retaining bars disposed longitudinally above said way and extending above said feed plunger to engage the wrappers when in initial folding position, a rear bottom flap folder disposed at the front end of said way and provided

with a plurality of slots, a shaft having a plurality of oppositely projecting fingers thereon adapted to swing to a vertical position at the front edge of said rear flap folder or to collapse into said slots, means for locking said shaft with its fingers in vertical position, a reciprocatingly mounted front bottom flap folder, reciprocating front end flap folders, rear and top and bottom end flap 10 folders and sealing means disposed at the sides of the way to act on the flaps as the articles are moved along the way.

9. In a wrapping machine, the combination of a way, a feed plunger reciprocating transversely of said way, a wrapper feed means for delivering wrappers in the path of said plunger, a rear bottom flap folder disposed at the front end of said way and provided with a plurality of slots, a shaft having a plurality of oppositely projecting fingers thereon adapted to swing to a vertical position at the front edge of said rear flap folder or to collapse into said slots, means for locking said shaft with its fingers in vertical position, a reciprocatingly mounted front bottom flap folder, reciprocating front end flap folders, and rear and top and bottom end flap folders and sealing means disposed at the sides of the way to act on the flaps as the articles are 30 moved along the way.

10. In a wrapping machine, the combination of a way, a feed plunger reciprocating transversely of said way, a wrapper feed means for delivering wrappers in the path of said plunger, a rear bottom flap folder disposed at the front end of said way and provided with a plurality of slots, a shaft having a plurality of oppositely projecting fingers thereon adapted to swing to a vertical position at the front edge of said rear flap folder or to collapse into said slots, means for locking said shaft with its fingers in vertical position, a reciprocatingly mounted front bottom flap folder, front end flap folders operatively associated with said front bottom flap folder to reciprocate therewith, a reciprocatingly mounted pusher member, and rear and top and bottom end flap folders disposed at the sides of the way to act on the flaps as the articles are moved along 40 the way.

11. In a wrapping machine, the combination of a way, a feed plunger reciprocating transversely of said way, a wrapper feed means for delivering wrappers in the path of said plunger, a pair of spaced wrapper retaining bars disposed longitudinally above said way and extending above said feed plunger to engage the wrappers when in initial folding position, a rear bottom flap folder 55 disposed at the front end of said way, a reciprocatingly mounted front bottom flap folder, front end flap folders operatively associated with said front bottom flap folder to reciprocate therewith, a reciprocatingly mounted pusher member, rear and top and bottom end flap folders disposed at the sides of the way to act on the flaps as the articles are moved along the way, said pusher 65

bottom end flap folders and sealing means disposed at the sides of the way to act on the flaps as the articles are moved along the way, said pusher member, end flap folders and sealing members having shouldered faces, and a delivery conveyor comprising belts coacting with the sealed ends of the packages and having stepped faces corresponding to the shouldered faces of said folding and sealing members. 70

12. In a wrapping machine, the combination of a way, a feed plunger reciprocating transversely of said way, a wrapper feed means for delivering wrappers in the path of said plunger, a pair of spaced wrapper retaining bars disposed longitudinally above said way and extending above said feed plunger to engage the wrappers when in initial folding position, a rear bottom flap folder disposed at the front end of said way, a reciprocatingly mounted front bottom flap folder, front end flap folders operatively associated with said front bottom flap folder to reciprocate therewith, a reciprocatingly mounted pusher member, and rear and top and bottom end flap folders disposed at the sides of the way to act on the flaps as the articles are moved along the way, said pusher member and end flap folders having shouldered faces. 80

13. In a wrapping machine, the combination of a way, a feed plunger reciprocating transversely of said way, a wrapper feed means for delivering wrappers in the path of said plunger, a rear bottom flap folder disposed at the front end of said way, a reciprocatingly mounted front bottom flap folder, front end flap folders operatively associated with said front bottom flap folder to reciprocate therewith, a reciprocatingly mounted pusher member, rear and top and bottom end flap folders and sealing means disposed at the sides of the way to act on the flaps as the articles are moved along the way, said pusher member, end flap folders and sealing members having shouldered faces, and a delivery conveyor comprising belts coacting with the sealed ends of the packages and having stepped faces corresponding to the shouldered faces of said folding and sealing members. 90

14. In a wrapping machine, the combination of a way, a feed plunger reciprocating transversely of said way, a wrapper feed means for delivering wrappers in the path of said plunger, a rear bottom flap folder disposed at the front end of said way, a reciprocatingly mounted front bottom flap folder, front end flap folders operatively associated with said front bottom flap folder to reciprocate therewith, a reciprocatingly mounted pusher member, and rear and top and bottom end flap folders disposed at the sides of the way to act on the flaps as the articles are moved along the way, said pusher 100

- member and end flap folders having shouldered faces
15. In a wrapping machine, the combination of an article conveying means including a reciprocating pusher, a plurality of flap folders acting in sequence on the said wrapper, sealing members coacting with the folded flaps, the said pusher, sealing members and certain of said flap folders having shouldered faces, and a delivery means having shouldered members coacting with the sealed ends of the wrapped articles.
16. In a wrapping machine, the combination of an article conveying means, a plurality of flap folders acting in sequence on the said wrapper, sealing members coacting with the folded flaps, the said sealing members and certain of said flap folders having shouldered faces, and a delivery means having shouldered members coacting with the sealed ends of the wrapped articles.
17. In a wrapping machine, the combination of an article feed and conveying means including a reciprocating pusher, and a plurality of flap folders acting in sequence on the said wrapper, the said pusher and certain of said flap folders having shouldered faces.
18. In a wrapping machine, the combination of an article feed and conveying means, and a plurality of flap folders acting in sequence on the said wrapper, the said flap folders having shouldered faces.
19. In a wrapping machine, the combination of an article conveying means including a way along which the articles are conveyed, flap folders disposed to coact with the ends of the article as they are carried along the way, said flap folders having shoulders disposed longitudinally of the way to receive projecting portions of the package, and sealing members disposed at the rear of the folders and also having shouldered faces.
20. In a wrapping machine, the combination of an article conveying means including a way along which the articles are conveyed, and flap folders disposed to coact with the ends of the article as they are carried along the way, said flap folders having shoulders disposed longitudinally of the way to receive projecting portions of the package.
21. In a wrapping machine, the combination of an article feed means including a way and a pusher having a shouldered face, and flap folders disposed to act on the flaps at the ends of the package and also having shouldered faces.
22. In a wrapping machine, the combination of an article conveying means, reciprocating front end flap folders provided with centrally disposed flap bending fingers, and rear end flap folders provided with projecting centrally disposed flap bending fingers, said fingers being adapted to initially shape and turn the folds prior to their engagement by the flap folders.
23. In a wrapping machine, the combination of an article conveying means, and flap folders provided with centrally disposed flap bending fingers adapted to initially shape and turn the flaps prior to their engagement by the flap folders.
24. In a wrapping machine, the combination of a way, reciprocating front end flap folders, rear end flap folders disposed at the sides of the way, top and bottom end flap creasing members disposed adjacent said rear end flap folders, creasing members reciprocating with said front end flap folders to coact with said top flap creasing members and constituting supports for the front flaps during the folding of the front and rear end flaps, and top and bottom end flap folders acting on said end flaps in sequence to the action of said creasing members.
25. In a wrapping machine, the combination of a way, reciprocating front end flap folders, rear end flap folders disposed at the sides of the way, top end flap creasing members disposed adjacent said rear end flap folders, creasing members reciprocating with said front end flap folders to coact with said top flap creasing members and constituting supports for the front flaps during the folding of the front and rear end flaps, and top and bottom end flap folders acting on said end flaps in sequence to the action of said creasing members.
26. In a wrapping machine, the combination of a way, a feed plunger reciprocating transversely of said way, a wrapper feed means for delivering wrappers in the path of said feed plunger, reciprocating front end flap folders, rear end flap folders disposed at the sides of the way, and top and bottom end flap creasing members disposed to act subsequent to said rear end flap folders.
- In witness whereof I have hereunto set my hand.
- CARL LITTLEFIELD.
